UNITED STATES PATENT OFFICE.

FRANK L. DYER, OF MONTCLAIR, NEW JERSEY, ASSIGNOR, BY MESNE ASSIGNMENTS, TO THOMAS A. EDISON, INCORPORATED, OF WEST ORANGE, NEW JERSEY, A CORPORATION OF NEW JERSEY.

BATTERY-WELL.

994,067.

Specification of Letters Patent. Patented May 30, 1911.

Application filed November 8, 1910. Serial No. 591,311.

To all whom it may concern:

Be it known that I, FRANK L. DYER, a citizen of the United States, and a resident of Montclair, in the county of Essex and State of New Jersey, have invented a certain new and useful Improvement in Battery-Wells, of which the following is a description.

My invention relates to battery wells and my object is to provide a device of this character of cheap but durable construction and one protecting the batteries inclosed therein from atmospheric and other deteriorating influences to a great extent. To this end, the walls of the well are formed of wood impregnated or indurated with a final infusible insoluble condensation product of phenol or creosol and formaldehyde or other equivalent agent containing the methylene radical CH_2 . If desired, the walls might be composed of fibrous material other than wood impregnated with the above mentioned condensation product or with the said condensation product mixed with any suitable inert filling material and molded to the desired form. Preferably, the walls are made double to form a heat insulating air space between the same.

In order that my invention may be more clearly understood, attention is hereby directed to the accompanying drawings, illustrating a vertical section through a battery well embodying one form of my invention and sunk in position in the ground.

It is well known that condensation products of the character above referred to may be used for indurating or impregnating wood or other fibrous or cellular material and rendering the same impervious to dry rot, and resistant to acids, alkalis, and other chemical agencies. I form the walls of my improved well of wood impregnated with such a material in any known manner. For example, the wood may be soaked with the ingredients necessary for the formation of the condensation product and the same

hardened in the pores of the wood by heat, either with or without the application of pressure. Or the walls may be formed of the condensation product containing any cheap filling body and molded either in an integral structure or in slabs which may be joined together.

The well 1 preferably is provided with a foundation or base 2 of any suitable material, and which may be of concrete, and with the inner and outer walls 3 and 4 formed, as stated, preferably of wood impregnated with a phenolic condensation product, the air space 5 being provided between the walls when double walls are provided. Batteries may be placed upon the shelves 6. The well may be provided with a neck 7 formed as a continuation of walls 3 and 4 and with the hinged cover 8. Also, if desired, a cover 9 may be seated upon the flanged ring 10 within the lower end of neck 7.

Having now described my invention, what I claim and desire to protect by Letters Patent is as follows:—

1. A battery well having walls of wood impregnated with a phenolic condensation product, substantially as described.

2. A battery well having walls of fibrous material indurated with a phenolic condensation product, substantially as described.

3. A battery well having double walls of fibrous material indurated with an infusible, insoluble final phenolic condensation product and having an air space between said walls, substantially as described.

4. A battery well having walls formed of an infusible insoluble final phenolic condensation product and an inert filling body, substantially as described.

This specification signed and witnessed this 3d day of November 1910.

FRANK L. DYER.
